UNITED STATES PATENT OFFICE.

STRICKLAND L. KNEASS, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

INJECTOR.

Application filed August 5, 1924. Serial No. 730,293.

To all whom it may concern:

Be it known that I, STRICKLAND L. KNEASS, a citizen of the United States, residing at Philadelphia, county of Philadelphia, and 5 State of Pennsylvania, have invented a new and useful Improvement in Injectors, of which the following is a full, clear, and exact description, reference being had to the accompanying drawings, which form 10 a part of this specification.

My invention relates to an improvement in method and apparatus for continuously supplying steam at low pressures to injectors.

15 The object of my invention is to provide an apparatus whereby steam within predetermined limits of pressure may be supplied to the low pressure part of an injector for example on a locomotive from the exhaust 20 of a working cylinder and whereby live steam will be automatically admitted to the injector supply pipe and expanded therein to meet the requirements of the low pressure part of the injector when steam is cut 25 off the working cylinder, whereby the injector may be continuously operated whether the locomotive be standing, drifting, or working.

30 A further object of my invention is to provide means whereby a substantially constant pressure will be maintained in the injector supply pipe, when the supply of steam is from the exhaust of the working cylinder, irrespective of variation in the 35 exhaust pressure.

Having now indicated, in a general way, the nature and purpose of my invention, I will proceed to a detailed description of a preferred embodiment thereof, with reference 40 to the accompanying drawings, in which—

Fig. 1 is a side elevation of a locomotive showing the application of my invention.

Fig. 2 is a sectional view of automatically 45 operated live and exhaust steam valves.

Fig. 3 is an end view, partly broken away, of the subject of Fig. 2.

Fig. 4 is a sectional view of a detail of my invention.

50 *a* indicates the boiler, *b* one of the cylinders, and *c* the steam chest of a locomotive. *d* indicates the injector for supplying water to the boiler and having the low pressure part *d'*, while *e* represents a manually con-

trolled main injector operating valve for 55 supplying live steam to the injector.

Exhaust steam from the cylinder passes through the conduit *f*, and the low pressure steam supply to the injector is through pipe *g*; the conduit *f* and the pipe *g* being, respectively connected to the body *h* in which 60 is a winged piston valve *i* adapted to control the passage of exhaust steam to the injector.

A pipe *j* connects the live steam valve *e* 65 with the body, the admission of live steam to pipe *g* being controlled by a valve *k*.

The valves *i* and *k* are opened or closed by steam chest pressure and are so arranged that when the locomotive is working the valve *i* 70 will permit the passage of exhaust steam to the injector, while when the locomotive is idle, as standing or drifting, the valve *i* will be automatically closed and the valve *k* automatically opened to permit the passage 75 to the injector of live steam, expanded to reduce its pressure. The construction of the mechanism for automatically operating the exhaust and live steam admission valves will be clear from the following description. 80

On the upper part of body *h* and in axial alignment with the valve *i* is a cylinder *l*, which is connected to the steam chest through a branch *m* and pipe *n*. Within the branch *m* is a piston *o* resting on a 85 plunger *p*, in turn resting on an outer piston *q* and connected by a major spring *r* with an inner piston *s* provided with a stem *t* which is connected with the valve *i*. An inner spring *u* surrounds the stem *t* and 90 abuts against a thimble *v* and the lower end of the cylinder. Communication between the exhaust conduit *f* and the inner piston *s* is constantly permitted through the aperture *w* in the cylinder and aperture *w'* in thimble 95 *v*. Clearance is provided between piston *q* and the upper part of cylinder *l* to permit communication between the upper part of the cylinder and atmosphere through 100 threaded aperture 15 to insure atmospheric pressure on the top of the piston *q*.

In operation, when steam is admitted to the steam chest, by opening the throttle of the locomotive, live steam pressure is exerted on the piston *o*, which is forced 105 down to the limit of its stroke and forces down the plunger *p* and outer piston *q*, which, acting through the major spring *r*,

causes the inner piston *s* and its stem *t* attached to the valve *i* to be moved downward, thus opening the valve and permitting exhaust steam to pass to the injector through 5 pipe *g* and at the same time compressing spring *u*. Exhaust steam from the conduit *f* passing through the apertures *w w'* exerts a pressure beneath the inner piston *s*, and, when the exhaust pressure rises, lifts the 10 piston, its stem and the attached valve *i* against the action of the major spring *r*, which abuts against the plunger *p*, which, under the steam chest pressure on piston *o*, acts as a fixed abutment. The valve *i* is 15 thus more or less closed by rise in exhaust pressure to be again returned to normal by the major spring with decrease in exhaust pressure, in order that the valve may act to automatically maintain a substantially constant pressure in the pipe *g*.

In the ordinary locomotive, or any reciprocating type of prime mover, both the inflow and outflow from the cylinders is intermittent. The discharge, therefore, from 25 the cylinder exhaust pipe is in periodic waves of high and low pressure, proportional to the impulse and frequency. Such variation in pressure is disturbing to the action of an injector, and I have devised 30 means to break the waves of pressure and induce a more even flow of exhaust steam to the regulating valve and injector, through the conduit *f* to valve *i*, and thence through the pipe *g* to the injector. In order to flatten out such waves and reduce the necessity 35 for throttling through the medium of inner piston *s*, there is set in the conduit *f* a body 12 of greater diameter than the conduit and divided into inner and outer chambers by 40 means of a cylindrical screen section 13, transversely of which is a baffle plate 14, the central portion of which is concaved, as shown in Fig. 4. Exhaust steam from the cylinder at varying pressures enters the cylindrical screen direct from conduit *f*, strikes the baffle and is deflected laterally through the meshes of the screen. The steam then 45 passes around the baffle and returns through the meshes of the screen into conduit *f* and thence to valve *i*. The effect of striking the baffle 14 is to eliminate a large part of the momentum of the peak of the wave of exhaust steam; the finely perforated cylindrical screen 13 breaks into small jets the 50 flow into the surrounding chamber, and this action is repeated when the steam passes through the other portion of the perforated screen into the conduit connected with the regulating valve. This eliminates the remaining impulses and gives a practically even and continuous discharge toward the 55 injector.

If steam be cut off from the steam chest, as when the locomotive is stopped or allowed to drift, the pressure is removed from piston

o and piston valve *i* will be closed by the action of spring *u*, which acts to lift the various parts into the position shown in Fig. 2.

On the upper part of the body *h* and adjacent to the cylinder *l* is a cylinder *x*, in axial alignment with the valve *k*, and connected through a branch *y* and pipe *n* with the steam chest. Within the cylinder *x* is a piston *z* which seats upon a port 2, between the lower portion of the cylinder and a chamber 3, which is connected to the main injector operating valve *e* by means of pipe *j*. Port 2 is also closed by an upwardly seating valve 4, provided with a cylindrical guide 5 having an aperture 6 for the passage of steam. The valve 4 is connected by means of a stem 7 to the outlet valve *k*, which controls a port affording communication between chamber 3 and an orifice 8 leading to the body *h* in such a manner that when one is open the other is 85 closed. The orifice 8 may be varied by adjustment of screw 9, which permits the size of the orifice to be such as to allow for the passage of only as much live steam as when expanded in body *h* will produce the pressure desired for the low pressure part of the injector. Suitable outlet space 10 and a conduit 11 leading to the exhaust pipe are provided to prevent accumulation of balancing pressure under the piston *z* or on top of 95 valve 4.

When pressure is on the steam chest, that is, when the cylinder is working, the valve *i*, as above described, is opened as a result of pressure on piston *o*. At the same time, steam chest pressure is on piston *z* and live steam pressure is present in chamber 3 and above valve 4 and acts to retain the valve 4 and outlet valve *k* in respectively open and closed position as shown in Fig. 2.

If now steam is shut off from the steam chest, pressure is relieved from the top of piston *z* and the piston is lifted by the pressure above valve 4, arising from the passage of steam from chamber 3 through aperture 6 in guide 5. When piston *z* is lifted, the pressure above valve 4 is dissipated to the exhaust pipe through the outlet space 10 and conduit 11. With pressure relieved from the top of valve 4, the pressure in chamber 3 acting beneath the valve lifts and closes it at the same time the valve *k* is lifted off its seat through its connection with valve 4, and live steam is permitted to pass to and through orifice 8 into body *h*, where it expands and passes to the injector through pipe *g* at desired pressure.

If now the locomotive be started up, steam chest pressure is again exerted on pistons *o* and *z*, the former seating on the base of its cylinder and the latter on port 2 closing the port from the live steam chamber 3. The pressure on piston *o* effects the opening of valve *i*, as above described. Pressure on piston *z* causes the piston to 130

- move down and, before it seats, to strike the upper end of stem 7 and move the steam, valve 4 and outlet valve *k* downward. This action is due to pressure on the larger area 5 of the piston *z* compared to the valve 4 even though the pressure in the steam chest is somewhat below that in chamber 3. After the preliminary downward movement of valve 4, steam from chamber 3, when the 10 injector operating valve *E* is open, passes through aperture 6 and equalizes the pressure on the top and under side of valve 4, so that the pressure of the steam closes the outlet valve *k* cutting off live steam from the 15 pipe *g*, which is then receiving exhaust steam as a result of the opening of valve *i*. Thus it will be noted that with the main injector operating valve *e* open the low pressure part of the injector is continuously supplied with steam either from the 20 exhaust, when the locomotive is working, or from the boiler when the locomotive is standing or drifting, and further that the continuous supply of steam is maintained 25 automatically.
- No claim is made herein for the process described as such has been made the subject matter of an application for patent filed by me as a division hereof.
- 30 Having now fully described my invention, what I claim and desire to protect by Letters Patent is:
1. In combination with an injector operated wholly or partly by exhaust steam, an exhaust regulating and cut-off valve, a live steam admission valve to the exhaust steam supply, and means to cause both valves to interact automatically.
  2. In combination with an injector operated wholly or partly by exhaust steam, an exhaust regulating and cut-off valve, a live steam admission valve to the exhaust steam supply, and means to cause both valves to interact automatically by live steam pressure controlled by the engine throttle.
  3. In combination with an injector operated wholly or partly by exhaust steam, an exhaust regulating and cut-off valve, a live steam admission valve operated by a piston subject to live steam pressure when the engine is running to admit exhaust steam to the injector supply with means for automatically obtaining independent controlling positions of its flow dependent upon exhaust pressure, a live steam admission valve operated by a piston subject to live steam pressure causing interaction of said valves to close the control valve when the live steam admission valve is open, and open the latter when the exhaust control valve is closed.
  4. Means for continuously supplying steam at low pressure to an injector on a locomotive having a working cylinder, comprising, in combination, means for admitting exhaust steam to the injector when the locomotive is working, means for admitting live steam at reduced pressure to the injector when the locomotive is not working, 70 and means controlled by live steam pressure whereby the injector is supplied with exhaust or live steam automatically as steam is put on or taken off the working cylinder.
  5. Means for supplying steam at low pressure to the injector on a locomotive, comprising a valve governing the admission to the injector of steam exhausted by the locomotive, a valve governing the admission of live steam to the injector, means for reducing the pressure of the live steam before its entry into the injector, said valves under the influence of live steam pressure being positioned to permit the passage of exhaust steam to the injector and prevent the passage thereto of live steam when the locomotive is working, and automatically to reverse and permit the passage of live steam to the injector when the locomotive is standing or drifting.
  6. Means for continuously supplying steam at low pressure to an injector on a locomotive having a working cylinder, comprising, in combination, an exhaust steam supply valve, a live steam supply valve, means associated with said valves adapted, under the influence of live steam pressure, to automatically reverse them to permit a supply of exhaust steam to the injector when the locomotive is working and a supply of live steam at reduced pressure when the locomotive is not working.
  7. Means for continuously supplying steam at low pressure to an injector on a locomotive having a working cylinder, comprising, in combination, an exhaust steam supply valve, a live steam supply valve, means associated with said valves adapted, under the influence of live steam pressure, to automatically reverse them to permit a supply of exhaust steam to the injector when the locomotive is working and a supply of live steam at reduced pressure when the locomotive is not working, and means associated with the exhaust steam supply valve adapted, under the influence of variations in exhaust pressures, to automatically maintain the pressure of the supply to the injector substantially constant.
  8. Means for continuously supplying steam at low pressure to an injector on a locomotive having a working cylinder and a steam chest associated therewith, comprising, in combination, a body, a conduit for exhaust steam leading from the working cylinder to said body, a conduit leading from said body to the low pressure part of the injector, a valve controlling the passage of exhaust steam to the injector, a live steam chamber, a passage connecting the

live steam chamber with said body, a valve controlling the passage of live steam through said passage, and means, acting automatically under the influence of live steam pressure, to open the exhaust steam controlling valve and close the live steam controlling valve when steam is admitted to the steam chest.

9. Means for continuously supplying steam at low pressure to an injector on a locomotive having a working cylinder and a steam chest associated therewith, comprising, in combination, a valve body, means affording communication between the cylinder and injector and said body, a valve in said body controlling the passage of exhaust steam from said cylinder to said injector, a piston in communication with said steam chest, means including a spring affording a flexible operating connection between said piston and valve, a second piston secured to said valve and in communication with said cylinder, a spring adapted to act to close said valve, and a valve adapted to act to automatically admit live steam to said injector when the cylinder is idle.
10. Means for continuously supplying steam at low pressure to an injector on a locomotive having a working cylinder and a steam chest associated therewith, comprising a valve body, means affording communication between said valve body and said injector and a source of live steam, a valve in said body controlling the passage of live steam to said injector, a piston in communication with said steam chest, a second piston connected to said valve, means affording communication between said piston and said body, a valve adapted to control communication between said last mentioned piston and said body, said first mentioned piston being adapted, when steam is put on the steam chest, to give said live steam control-

ling valve a preliminary closing movement and open the valve controlling communication between said body and said second piston whereby said live steam valve will be closed by live steam pressure, and a valve adapted to automatically open when steam is put on the steam chest to admit exhaust steam to the injector.

11. Means for continuously supplying steam at low pressure to an injector on a locomotive having a working cylinder and a steam chest associated therewith, comprising the combination with automatically actuated valves for supplying exhaust steam to the injector when the cylinder is working and live steam when the cylinder is idle, of an enlarged section in the exhaust conduit, a cylindrical screen of less diameter than, and positioned in, said section axially thereof, and a baffle plate of less diameter than said section extending transversely of said screen intermediate its ends.

12. Means for continuously supplying steam at low pressure to an injector on a locomotive having a working cylinder, comprising, in combination, means for admitting exhaust steam to the injector when the locomotive is working, means for admitting live steam at reduced pressure to the injector when the locomotive is not working, means controlled by live steam pressure whereby the injector is supplied with exhaust or live steam automatically as steam is put on or taken off the working cylinder, and means adapted, under the influence of variations in exhaust pressures, to automatically maintain the pressure of the supply of exhaust steam to the injector substantially constant.

In testimony of which invention, I have hereunto set my hand, at Philadelphia, Pa., on this 1st day of August, 1924.

STRICKLAND L. KNEASS.
